DESIGN FOR A BROILER GRILL

Erik G. Grundstrom, Chicago, Ill., assignor to Advance Aluminum Castings Corp., Chicago,
Ill., a corporation of Illinois

Application September 1, 1939, Serial No. 87,002

Term of patent 7 years

To all whom it may concern:

Be it known that I, Erik G. Grundstrom, a citizen of the United States, residing at Chicago, in the county of Cook and State of Illinois, have invented a new, original, and ornamental Design for Broiler Grill, of which the following is a specification, reference being had to the accompanying drawing, forming part thereof.

I claim:

The ornamental design for a broiler grill, substantially as shown.

ERIK G. GRUNDSTROM,
